Inventor
Joseph N. Curry.
By Harry D. Wallace.

Attorney.

UNITED STATES PATENT OFFICE.

JOSEPH W. CURRY, OF BREWERTON, NEW YORK, ASSIGNOR OF ONE-HALF TO JOSEPH CURRY, JR., OF BREWERTON, NEW YORK.

COLLAPSIBLE CRATE.

Application filed April 21, 1926. Serial No. 103,483.

This invention relates to collapsible crates, and has for its primary object to provide an all-metal container especially adapted for packing and shipping various products or goods in bulk, that are coarser than the ordinary grains. A further object is to provide a crate that is easily portable and may be readily collapsed when empty for returning to the shipper, or for storing in a relatively small space. A further object is to provide a crate of the character set forth, wherein the sides, ends, top and bottom are all hingedly connected and are constructed and arranged to be folded and unfolded without detaching any of the parts. A further object is to provide a novel frame by which all the hinged or movable parts are supported and controlled, the said frame directly supporting the top and bottom members, and also serving as a guide for facilitating the folding or collapsing of the ends of the crate. And a further object is to provide novel means for extending or enlarging the crate, in the direction of its transverse dimension, for increasing the capacity of the container.

I attain these objects by the means set forth in the detailed description which follows, and as illustrated by the accompanying drawings, in which—

Figure 1 is a top plan view of the normal crate ready for loading or shipment. Fig. 2 is a side elevation of the same. Fig. 3 is a top plan view of the normal crate with the hinged covers thrown open. Fig. 4 is a top plan view, showing the crate partially collapsed. Fig. 5 is an end view of the crate shown in Figs. 1, 2 and 3. Fig. 6 is a broken end view and partial vertical transverse section, the latter being taken on line 6—6 of Fig. 3, showing the means for hinging the end members that are slidably mounted in the frame. Fig. 7 is a fragmentary vertical longitudinal section, taken on line 7—7 of Fig. 6. Fig. 8 is a top plan view of the crate extended transversely. Fig. 9 is an end elevation of the same. Fig. 10 is respectively a vertical longitudinal section on line 10 of Fig. 3 and a transverse section on line 10' of Fig. 3. Fig. 11 is a reduced plan view of one of the bottom members. And Fig. 12 is respectively a vertical longitudinal section, and a vertical transverse section taken on lines

12 and 12' of Fig. 1; showing the latch 55 engaging the partition members.

The drawings show all of the sheet-metal parts exaggerated as to thickness for clearness.

In the drawings, 2 represents an open oblong frame, preferably made of similar relatively heavy endless wire members 2'—2^a, which are disposed parallel to each other in vertical planes, and the said members are preferably permanently tied and reinforced 60 medially at the top and bottom, and also at the opposite ends, by suitable sheet-metal clips or clamps 2^b—2^c and 2^d—2^e, which may be held rigidly in place by solder or other suitable means. Midway between its ends, the frame 2 is fitted with an upright post 3 which is preferably disposed between the members 2'—2^a and passes through and is rigidly secured to the clips or sleeves 2^b—2^c, as shown in Figs. 1, 2, 3 and 4. The opposite sides of the crate, consist of plain sheets of metal 4—4' that extend the full length and height of the crate. The top and bottom, as well as the end margins of the side members 4—4', are similarly formed with 70 hinge-loops 4^a—4^b that receive horizontal pintles 5—5', and vertical pintles 6—6'. 7 and 8 represent similar bottom members, which are formed respectively with hinge-loops 7' and 8' that receive the horizontal 75 pintles 5', by which the said members are adapted to swing to the extent shown by dotted arcs 7^a—8^a, in Fig. 5. When extended the free end portions of the members 7 and 8 rest upon the lower horizontal 80 portion of the frame 2 and also overlap each other, as shown in Figs. 3 and 5, the said members preferably being slotted transversely, as at 7^b and 8^b, for straddling the post 3 (see Fig. 11). 9 and 9' represent swingable vertical partition members, which are pivoted or hinged to the opposite side members 4—4' by pintles 9^a, the latter being supported by similar vertical plates 9^b, that are secured to the sides 4—4' by rivets 9^c. The partitions 9—9' when extended, (see 85 Figs. 1, 2, 3 and 5) preferably engage the opposite sides of the post 3, to which they may be fastened by any suitable means, as by spring-latches 9^d (see Figs. 3 and 10). The partitions 9—9' when extended, tend to 90 hold the bottom members 7 and 8 in place and in firm contact with the bottom por-

tion of frame 2. To collapse the crate, the partition 9-9' must be swung away from the post 3 towards the corresponding side members 4-4', as shown by the dotted arcs 5 in Fig. 3. The bottom sections 7 and 8 may then be swung upwardly and laterally against the opposite side members, as indicated by the dotted arcs in Fig. 5.

The opposite ends of the crate are preferably constructed exactly alike, and are designated generally by the numeral 10. Each end comprises similar sheet-metal members 10', which overlap and slidably interlock with similar members 10^a, by means of which 15 the several pairs of said members are rendered extensible. The members 10' are formed at their corresponding ends with hinge-loops 10^b, that respectively receive and pivot upon the pintles 6-6', while the members 10' of both pairs are hinged to an oblong vertically disposed wire part comprising parallel pintles 12, as best seen in Figs. 5, 6 and 7. The end members 10'-10^a are interlocked to each other by means of integral guide-lugs 10^c-10^d which loosely engage or grip the top and bottom edges of said members, as shown in Figs. 1, 3, 4 and 5. The connected pintles 12 are pivotally supported at their top and bottom ends by sleeves 13-13', which are slidable on the horizontal portions of the frame 2 (see Figs. 3, 4 and 7) the said sleeves being formed with depending loop-arms 13^a, which engage the top and bottom ends of the pintles 12, as shown in Figs. 4, 5, 6 and 7. The ends 10 are normally held extended, as shown in Figs. 1, 3 and 5, by the bottom members 7 and 8 when the latter are extended, as shown in Fig. 3, and when the partitions 9-9' and the bottom members are collapsed, the ends 10 may be folded inwardly by simultaneously sliding the sleeves 13-13' towards the post 3, as shown in Fig. 4. This collapsing of the ends 10 may be effected by 40 the operator applying pressure against the opposite side members 4-4', in a well-known manner. 14-14' represent the sectional cover for the crate, which comprises similar sheet-metal plates, each of which is formed at its outer edge with hinge-loops 14^a, that receive and are swingable on the horizontal pintles 5. The cover 14 is preferably narrower than the member 14', and should be closed first. In the preferred construction, the free longitudinal edge of member 14 rests upon the nearest wire, as 2', of the frame 2, while the member 14' is preferably broader and extends beyond the frame 2' and at the same time overlaps the free 45 edge of the member 14, as shown in Fig. 5. The cover members are preferably held in the overlapped position by the post 3, the member 14' being provided with a slot or opening 14^b that receives the projecting upper end of the post, as shown in Figs. 1 and 5. The top end of post 3 is preferably perforated, and the cover members may be held from accidental release, by the insertion of a cotter-pin or other fastening device 15, through the opening of the post, as shown 50 in Figs. 2 and 8.

Cover members 14 and 14' are provided respectively with extensible leaves or plates 14^c-14^d which are preferably slidably disposed beneath the said members, and are held in place and rendered extensible by means of rivets 16, which play in slots 14^e of the said leaves, as best seen in Figs. 1, 8 and 9. Figs. 8 and 9 show the crate extended laterally for increasing its capacity, when such arrangement of the crate is desirable. The leaf 14^c is preferably provided with a slot or opening 14^f, for interlocking said part with the post 3, the same as the member 14'. The bottom members 7 and 8, as well as the partitions 9 and 9', are preferably made broad enough to permit the extension of the crate, as shown in Figs. 8 and 9, without altering the said parts.

In order to hold the crate in the normal condition, as shown in Figs. 1, 2 and 3, as well as in the extended position, shown in Figs. 8 and 9, for preventing accidental expansion and contraction of the body laterally, I provide a latch which comprises an L-shaped part 17, having a horizontal arm 17' which is rigidly secured to the under side of the extensible leaf 14^c, by rivets 17^a, and having a depending arm 17^b, which engages coinciding notches 9^e-9^d formed in the top edges of the partitions 9-9', as shown in Figs. 1 and 3. The notches 9^e-9^d are only engaged by the latch when the crate is contracted, as shown in Figs. 1, 3 and 5, and effectually prevents the extension of the crate laterally until the cover member 14 is lifted for freeing the latch. When, however, the crate is extended laterally, as shown in Figs. 8 and 9, the partitions 9-9' are moved past each other to the extent shown in Fig. 8. This shifts the notch 9^e out of register with the notch 9^d and into register with another notch 9^e formed near the free end of partition 9, so that when the leaf 14^c is extended beyond the cover 14, the latch 17 approaches close to the post 3 and drops into the notches 9^e and 9^e (see Figs. 8 and 9) and prevents the contraction of the crate until the cover member 14 is lifted away from the frame 2.

The gaps or openings that occur between the cover and bottom members and the ends 10, in both the plan and end elevations throughout the drawings are exaggerated for clearness. These openings in practice, are relatively narrow for preventing the escape of the contents of the crate.

My collapsible and extensible crate is extremely simple, and when constructed from sheet material of suitable gauge is light

and yet durable. The collapsing and extending of the parts of the normal crates, shown in Figs. 1 to 5, inclusive, may be effected in less than a minute even by unskilled persons. When the crate is fully collapsed, it may be stored in a relatively small space.

Having thus described my invention, what I claim, is—

1. A crate comprising a rectangular body, the side and end members thereof being hinged at the four corners, bottom members hinged to the lower edges of the side members and overlapping near the middle of the body, partition members hinged to the side members intermediate their ends adapted to be extended across the middle of the body and to overlap each other, an open oblong floating frame extending lengthwise and centrally across the body, the bottom portion of the frame being disposed below the bottom members, pintles supported by the ends of the frame and pivotally supporting the facing ends of the end members, and cover members hinged to the top margins of the side members and overlaying and supported by the top portion of the frame.

2. A crate comprising a rectangular body, the side and end members thereof being hinged at the four corners, bottom members hinged to the lower edges of the side members and overlapping near the middle of the body, partition members hinged to the side members intermediate their ends adapted to be extended across the middle of the body and to overlap each other, an open oblong floating frame extending lengthwise and centrally across the body, the bottom portion of the frame being disposed below the bottom members, pintles supported by the ends of the frame and pivotally supporting the facing ends of the end members, cover members hinged to the top margins of the side members and overlaying and supported by the top portion of the frame, and means carried by one of said cover members and engaging said partition members for preventing accidental expansion, contraction or collapsing of said body.

3. A crate comprising a rectangular body, the side and end members thereof being hinged at the four corners, said end members being arranged in pairs, the side members having hinge-loops at their top and bottom edges, bottom members hinged to the lower edges of the side members and overlapping near the middle of the body, partition members hinged to the side members adapted to be swung across the middle of the body and to be overlapped, an open frame extending lengthwise around the body, the bottom portion of the frame being disposed below the bottom members, twin pintles movably supported by the ends of the frame and pivotally supporting the facing ends of the

end members, and cover members hinged to the top margins of the side members and overlaying the top portion of the frame.

4. A crate comprising a rectangular body, the side and end members thereof being hinged at the four corners, said end members being arranged in pairs, the side members having hinge-loops at their top and bottom edges, bottom members hinged to the lower edges of the side members and overlapping near the middle of the body, partition members hinged to the side members adapted to be swung across the middle of the body and to be overlapped, an open frame extending lengthwise around the body, the bottom portion of the frame being disposed below the bottom members, twin pintles movably supported by the ends of the frame, and pivotally supporting the facing ends of the end members, cover members hinged to the top margins of the side members and overlaying the top portion of the frame, means for expanding said body laterally, and means carried by one cover member and engaging said partition members for preventing accidental expansion, contraction or collapsing of said body.

5. In a collapsible crate, side and end members hinged together at the four corners of the crate, a bottom and a top member hinged to each side member, an open oblong wire frame disposed in the line of the longitudinal center of the crate, the end members being disposed within the opening of the frame, the bottom members adapted to be overlapped upon the bottom portion of the frame, partition members hinged medially to the opposite side members and swingable in a horizontal plane above the bottom members adapted when extended to prevent the upward swinging of the bottom members, and said bottom members when extended adapted to hold the end members parallel to each other, means slidable on said frame for supporting the facing ends of the end members, and means for interlocking one of the top members when extended with the top portion of the frame.

6. In a collapsible crate, a frame comprising similar endless wires, clamps for rigidly holding said wires parallel to each other, a post disposed vertically in said frame and rigidly supported by said clamps, an oblong hollow body comprising side members disposed parallel to said frame, end members arranged in pairs hinged to the side members and pivotally supported between the top and bottom portions of said frame, bottom members hinged to the lower margins of the side members adapted when extended horizontally to be overlapped upon the bottom portion of the frame, swingable partition members hinged to the medial portions of said side members adapted when extended to parallel the end members and to hold the

- bottom members against the frame, means 55
slidable on the horizontal portions of the
frame for swinging the end members to-
wards each other for collapsing the crate,
cover members hinged to the opposite side
members adapted to be overlapped across the
top portion of said frame, and means for
interlocking the cover members with said
post.
- 10 7. A collapsible crate comprising an ob-
long hollow body having parallel side mem-
bers, extensible end members arranged in
pairs for connecting the ends of the side
members, the side and end members being
15 formed with complementary hinge loops, an
open wire frame encircling the body in the
line of its longitudinal center, sleeves mount-
ed near the ends of said frame and slidable
on the horizontal portions thereof, twin
20 pintles supported by said sleeve to which the
facing ends of the end members are pivoted,
similar bottom members hinged to the bot-
tom margins of the side members and over-
lapping each other upon the bottom portion
25 of the frame, similar partition members
hinged to the inner walls of the side mem-
bers adapted when extended transversely to
prevent the raising of the bottom members,
the said bottom members adapted when ex-
30 tended horizontally to prevent the inward
collapsing of the end members, similar cover
members hinged to the top margins of the
respective side members adapted when ex-
tended horizontally to overlap upon the top
35 portion of the frame and means carried by
one cover member and engaging said parti-
tion members for preventing accidental ex-
pansion and contraction of the body lat-
erally.
- 40 8. In a collapsible crate, a body compris-
ing side and end members hinged together
at the four corners of the body, bottom mem-
bers of less breadth than the body hinged to
the bottom margins of the side members, an
45 oblong open frame comprising two continu-
ous parallel wires encircling the body longi-
tudinally, clamps rigidly applied to the top
and bottom, medial portions of said frame,
said end and said bottom members being dis-
50 posed within the opening of said frame,
sleeves slidably mounted near the ends of the
top and bottom portions of said frame and
pivotally supporting the facing ends of the
end members, partition members hinged to
55 the opposite side members adapted to be ex-
tended parallel to the end members for di-
viding said body in two compartments, cover
members hinged to the opposite side mem-
bers, their free lateral margins overlapping
60 on the top portion of the frame, means for
interlocking one cover member with the par-
- tition members, and means for interlocking
cover members to the frame.
9. In a collapsible crate, an oblong hollow
body comprising side members having hinge-
loops at their top, bottom and end margins,
bottom members hinged respectively to the
bottom margins of said side members, a
frame comprising similar strands of wire
disposed parallel to each other extending
longitudinally across said body, said wires
being tied together medially by clamps, guide
clips slidably mounted near the ends of the
horizontal portions of said frame, twin pint-
les pivotally supported by said guide clips,
end members arranged in pairs hinged re-
spectively to said pintles and to the end
margins of the corresponding side members,
said ends adapted to be collapsed by the in-
ward sliding of said guide clips toward said
clamps, a post extending vertically through
said frame and being held rigidly by said
clamps, cover members hinged to the top
edges of said side members, their free ends
overlapping each other directly over the top
portion of said frame and one of said mem-
bers adapted to interlock with said post, and
means for extending said cover members and
said end members laterally for increasing
the capacity of the crate.
10. A crate comprising a rectangular hol-
low body, the side and end members being
hinged at the four corners whereby the end
members may yield inwardly substantially on
the medial longitudinal line of the body for
collapsing the crate, bottom members hinged
to the lower edges of the side members and
overlapping each other near said medial line
adapted to be extended laterally for increas-
ing the breadth of the crate, said bottom
members adapted to prevent the collapsing
of the end members while the bottom mem-
bers are extended, an open floating rectan-
gular frame enclosing the body in a vertical
plane that coincides with said medial line,
means slidable on the top and bottom por-
tions of the frame for facilitating the in-
ward folding of the end members when the
bottom members are swung upwardly to-
ward the corresponding side members, parti-
tion members hinged to the side members,
each partition member extending past said
medial line and being overlapped, cover
members hinged to the top margins of said
side members adapted to be swung toward
said medial line and to be overlapped upon
and supported by the top frame portion, and
means for interlocking said cover members
with said partition members.
- In testimony whereof I affix my signature.

JOSEPH W. CURRY.
